UNITED STATES PATENT OFFICE.

HENRY EMANUEL TRAUB, OF PEKIN, ILLINOIS.

FOLDING BOAT.

SPECIFICATION forming part of Letters Patent No. 670,942, dated April 2, 1901.

Application filed May 18, 1900. Serial No. 17,142. (No model.)

To all whom it may concern:

Be it known that I, HENRY EMANUEL TRAUB, a citizen of the United States, residing at Pe-
kin, in the county of Tazewell and State of
Illinois, have invented a new and useful Fold-
ing Boat, of which the following is a specifi-
cation.

This invention relates to boats in general,
and more particularly to the class of folding
boats formed of fabric stretched upon suit-
ably-formed frames, the frames being formed
to be jointed and disjoined to set up and take
down the boat, the object of the invention be-
ing to provide a simple and efficient construc-
tion wherein the parts of the boat may be
folded to occupy a small compass and which
when assembled operatively will form a rigid
and efficient construction.

Further objects and advantages of the in-
vention will be evident from the following
description.

In the drawings forming a portion of this
specification, and in which like numerals of
reference indicate similar parts in the several
views, Figure 1 is a perspective view showing
the complete boat when set up. Fig. 2 is a
longitudinal central section of the boat when
set up. Fig. 3 is a transverse section taken
through the boat when set up. Fig. 4 is an
elevation view showing one end of the boat
and illustrating the double stem and the ar-
rangement of the keelsons with respect to the
double stem. Fig. 5 is a plan view showing
the gunwales and the reinforcements thereof.
Fig. 6 is a plan view showing a removable and
adjustable thwart. Fig. 7 is a perspective view
showing the removable and folding keelson.
Fig. 8 is a detail perspective view showing
one of the socket-plates in which the upper
ends of the ribs are engaged.

Referring now to the drawings, the present
boat comprises a main keelson 10, comprising
end pieces 11 and 12, which are disposed in
axial alignment and are connected by means
of side plates 13 and 14, which overlap at their
ends the adjacent ends of the end pieces and
are held thereagainst by transversely-dis-
posed bolts 15, provided with thumb-nuts 16.
At each end of the plates there are two of
these clamping-bolts, and by removing one of
them the plates may be folded, or, rather, the

end pieces may be folded to lie between the
plates, or, if preferred, the end pieces may
be entirely disjoined from the plates.

In the outer ends of the end pieces 11 and 55
12 are formed axial perforations, with which
are engaged the ends of stems 17 and 18, which
are made of spring-metal rods and are pro-
vided with eyes 19 and 20 at their free ends.

In the under edges of the side plates 13 and 60
14 are formed recesses 21, with which are en-
gaged the ribs 22 of the boat-frame, and the
free ends of which ribs are engaged with the
socket-plates 23, the functions of these plates
being hereinafter explained. The plates 23 65
are each formed of a single section of sheet
metal bent upon itself and one layer thereof
having a struck-up portion which forms the
socket to receive the rib end. The ribs are
held in recesses 21 by means of hooks 25, 70
which are pivoted on the outer faces of the
plates and are adapted to swing down and
under the ribs, as illustrated in Fig. 2 of the
drawings, and additional ribs 26 are seated
in recesses 27 in the upper faces of the end 75
pieces 11 and 12 and are held in place therein
by hooks 28, which are pivoted to the side
faces of the end pieces, as shown.

The fabric covering for the frame consists
of two thicknesses or layers which are fitted 80
snugly over the frame, and the upper edges
of the fabric are folded inwardly and sewed
to form pockets to receive the gunwales. The
gunwales consist of two sections 30 and 31,
each comprising two arms which are cur-
vingly diverged to form the end sections of
ellipses, the bights of these end sections be-
ing engaged with the eyes in the ends of the
stems 17 and 18. The mutually adjacent ends
of these sections 30 and 31 lie against the ends 90
of arc-shaped sections 32 and 33 to complete
the ellipse, and the joints are covered by re-
inforcing sections or rods 34. Both the gun-
wale-sections and the reinforcing-rods are
held in the pockets, and the outer end of each
reinforcing-rod is projected through an open-
ing in the inner layer of fabric and is bent
into the form of an eye to facilitate with-
drawal thereof and permit folding of the re-
moved fabric on the lines of the joints of the 100
gunwale-sections.

Below the pockets which receive the gun-

- wales are formed additional pockets, as shown, by sewing through both thicknesses of fabric in parallel lines, and in these additional pockets are disposed keelsons 35, each of which 5 consists of two end sections, similar to the end sections of the gunwales, the mutually adjacent ends of which are separated, and the resultant interspace is bridged by an arc-shaped section 36 at each side, the joints of these several sections being lapped by reinforcing-rods 37, which are similar in form and arrangement to the reinforcing-rods of the gunwales. It will be thus seen that the gunwales are counterparts of the side keelsons therebelow and that when the fabric covering is removed from the frame and the reinforcing-rods withdrawn the entire fabric may be folded. 10 Beneath the keelson 10 and between the two layers of fabric are formed two pockets 20 at opposite ends of the boat, and in these pockets are disposed the lower ends of arc-shaped stems 40 and 41, the upper portions of which conform to the curvatures of the stems 17 and 18, the several keelsons 35 being held between the inner and outer stems, as shown, and the bights of the rods forming these keelsons being brought through the inner fabric and disposed directly against the outer faces of the inner stems 17 and 18. 25 In order to brace the boat amidships, an adjustable thwart is employed and comprises two beams 42 and 43, having each a series of perforations adapted for alinement and to receive clamping-bolts 44 and 45 to hold them 30 in mutual relation, these bolts permitting the beams to be adjusted to lengthen or shorten the resultant thwart. At the outer end of each beam is pivoted a head 46, which is arc-shaped to lie against the inner face of the boat at the gunwales thereof, and which heads each have plates 47 secured adjacent its ends and bent upwardly and outwardly to form hooks adapted for engagement over the gunwales. The heads 46 are pivotally held to 35 the beams of the thwart by bolts 48, which are passed upwardly and outwardly through the ends of the beams and through perforations in the heads. By this means the heads may be adjusted to lie snugly against the inner face of the boat and may be moved outwardly to hold the structure with great stiffness. In practice the floor-sections are laid directly upon the ribs. 40 With the above construction it will be seen that there is provided a boat having its frame, with the exception of the main keelson 10, formed of steel, while the parts are so formed and combined that the boat may be readily

set up and taken down and when taken down may be folded into a small compass. 60

It will of course be understood that in practice various modifications of the structure shown may be made and that any suitable materials and proportions may be used for the various parts without departing from the spirit of the invention. 65

What is claimed is—

1. A boat comprising a frame including a main keelson having stem-pieces connected therewith, ribs held to the main keelson, a covering fabric for the frame having pockets, keelsons disposed in the pockets and lying exteriorly of the stem-pieces, pockets below the main keelson, and additional stem-pieces disposed in the last-named pockets and lying exteriorly of the keelsons. 75

2. A boat comprising a frame including keelsons formed in sections with their ends abutting, and reinforcing members lapping the abutting ends, said keelsons and reinforcing members being held in fixed relation. 80

3. A boat comprising a frame including keelsons formed in sections with their ends abutting, reinforcing members lapping the abutting ends, and a fabric covering for the frame including pockets which receive the keelsons and reinforcing members and from which the latter project inwardly of the boat. 85

4. A boat comprising a frame including keelsons, ribs, stems, gunwales and cover, and an adjustable thwart comprising beams adjustably connected and having pivoted arc-shaped heads adapted to lie against the inner face of the boat adjacent the gunwales. 90

5. The combination with a boat of a removable and adjustable thwart comprising beams adjustably connected, arc-shaped heads pivoted to the ends of the beams and adapted to lie against the inner face of the boat, and hooks upon the heads for engagement over the gunwales. 95

6. A boat comprising a frame including keelsons formed in sections with their ends abutting, reinforcing members lapping the abutting ends, and a fabric covering for the frame including layers united to form pockets which receive the keelsons and reinforcing members and from which the latter project inwardly of the boat. 105

In testimony that I claim the foregoing as my own I have hereto affixed my signature in the presence of two witnesses.

HENRY EMANUEL TRAUB.
